UNITED STATES PATENT OFFICE.

EMIL SCHILL, OF NEW YORK, N. Y., ASSIGNOR TO CONTINENTAL GAS COMPRESSING CORPORATION, OF NEW YORK, N. Y., A CORPORATION OF NEW YORK.

PROCESS OF OBTAINING LIQUID HYDROCARBONS.

13,829.

Specification of Reissued Letters Patent. Reissued Nov. 17, 1914.

Original No. 1,100,260, dated June 16, 1914, Serial No. 724,947. Application for reissue filed June 19, 1914. Serial No. 846,206.

To all whom it may concern:

Be it known that I, EMIL SCHILL, a citizen of Wurttemberg, Germany, and a resident of New York city, New York, have invented certain new and useful Improvements in Processes of Obtaining Liquid Hydrocarbons, of which the following is a specification.

This invention relates more particularly to the recovery in isolated liquid form of hydrocarbons of the methane series, that is hydrocarbons having a general formula of C_nH_{2n+2} . As typical of the process, I will refer in this specification throughout to the hydrocarbons pentane, C_5H_{12} , but it is understood that my process is equally applicable to the isolation and recovery of the adjacent hydrocarbons like hexane, etc.

The invention relates in its more specific form to the recovery in isolated form of such hydrocarbons of the methane series which have a boiling point between 0 and 70° C.

Several of the most important problems of modern industrial chemistry have been reduced to the question of obtaining pentane (or its homologues) in large quantities and at reasonable prices. These hydrocarbons are known chemical bodies existing in the form of various isomers, of which the iso variety is more particularly the object of this invention, but the known methods of production are attended with so much difficulty and expense as to practically make pentane or its homologues unknown bodies when considered as commercial commodities to be obtained in quantities and at prices that will make them available in connection with a large industrial enterprise.

My invention is based upon a series of observations, chief among which are the following: I determined first that in order to obtain pentane in large quantities I should discard any idea of a synthetic method of production as well as any idea of producing the product itself by chemical methods. Next in searching for pentane among natural existing products I find that it occurs in relatively large quantities in natural gas of the kind known as "wet gas". It also occurs in fair quantities in natural petroleum as a product directly contained therein. Having thus determined upon the nature of the starting material, I next elimi-

nated and discarded various methods involving the direct extraction of pentanes out of the gases in their natural condition in the one case or the direct extraction or distillation of the pentanes from the petroleum in the other, and decided to adopt an indirect method. Although such indirect method involves additional steps, I find that ultimately it is better than any direct method.

In carrying out my invention in that particular manner which is illustrated in the drawing, I proceed as follows: In that case the starting material is natural wet gas and I first convert it, or rather such parts of it as contain hydrocarbons having a boiling point of from 0° C.-70° C. into the form of a liquid. Such liquid, if kept in a confined state, at pressures and temperatures which will prevent the volatilization of the hydrocarbons which have been liquefied, will contain among its ingredients pentanes and their homologues. Thereafter, provided the liquid is maintained in approximately the condition of its creation, the pentanes or their homologues can be separated by fractional distillation or by some special process. Such fractional distillation may, of course, be repeated several times, if desired, for the purpose of isolating the various hydrocarbons or their various isomers. Any hydrocarbon gases which are not liquefied under the conditions specified may be used as fuel or for other commercial purposes, as may also be the liquid remaining after the extraction of the pentanes. In other words, the invention consists in its essence in a process according to which hydrocarbons when found to have pentanes in admixture therewith are first brought to, or taken in, a gaseous condition. From this gaseous mixture the pentanes or other desired homologues are not extracted directly but they are extracted only after the entire gaseous mixture is first compressed under conditions minimizing the heat of compression and then only after there has been a separation of some of the gaseous ingredients from the compressed gas mixture. After the pentanes are brought into this condition of separation (i. e., the condition in which they are no longer accompanied by the vapors of the higher boiling substances such as gasoline), they are reduced from the gaseous condition

into isolated liquid form. Working on these general principles I have discovered that for the purpose of securing commercial results, there must be employed a more or less special means of converting the hydrocarbon gases into liquids. Refrigeration and other similar methods were discarded as impractical. I selected and applied a process according to which the hydrocarbon gases are treated under pressure with a finely divided heat absorbing medium. The agent should enter the compression cylinder in a finely atomized form such as a spray or mist. A pressure of 350 pounds in the cylinder is sufficient to bring about commercial results, but a lower pressure may also be used. The pressures and temperatures should be such that the hydrocarbon gases remain in their gaseous condition. The heat absorbing agent should also remove from the gases all the water contained in them in form of an aqueous vapor, and therewith all the water soluble impurities like NH_3 , H_2S and others, as well as heavier products like tar. It also absorbs the heat generated by compression. The agent is subsequently recovered while the compressed gases are passed through cooling chambers wherein they are converted into liquid form. The temperature in the several cooling chambers is regulated in such a manner as to convert all the hydrocarbon ingredients with the exception of the so-called "permanent gases" to separate liquid form. In the processes carried out in the apparatus shown in the drawing, there is first produced a liquid composed of hydrocarbons containing as some of its ingredients the pentanes in fair proportion. It is important that at this point the temperatures and pressures be so regulated that the liquid will be maintained at a temperature below that favorable to the evaporation of the pentanes. Any process which involves a further treatment of this liquid without maintaining such conditions or a process which involves the drawing off of such liquid into barrels or the like for storage and shipment, whereby the liquid becomes subjected to ordinary atmospheric conditions, is unsuitable and useless for my purposes, inasmuch as for instance the isopentane having a boiling point of approximately 30° C . becomes volatilized and dissipated in the air and is thus irrecoverably lost. The hydrocarbons which have not become liquefied in the process above mentioned may pass out of the chamber containing the liquefied hydrocarbons and be subjected to further commercial use, but only under conditions which will insure the maintenance of the pentanes in liquid form. From this liquid mixture of hydrocarbons containing pentanes the pentanes may be distilled off by fractional distillation as may also the homologues of the pentanes which

are present in liquid form. When, as the result of such distillation, the pentane isomers or their near homologues have been collected either in one vessel or separate vessels, in liquid form they are filled into metal tanks or cylinders and sealed to prevent volatilization.

In the case of natural petroleum which contains the pentanes, care must be taken not to permit the volatilization of the pentanes during their collection and further treatment. By heating such a petroleum say to 70° C . a certain variety of hydrocarbons including pentanes are driven off and passed through the above described compression treatment until they become liquefied. However with liquid mixtures of this character the volatilization of the low boiling ingredients is retarded and the temperature may be advantageously increased, to secure a more nearly quantitative yield. The liquid so obtained consisting substantially of pentanes, but containing a proportion of its nearest homologues, may be filled in steel cylinders directly and sealed or they may be further isolated by fractional distillation or otherwise, as above described.

I have employed a number of heat absorbing agents all of which have—as they must—the quality of absorbing water, of being good conductors of heat, of having lubricating qualities, the property of chemical neutrality with respect to any of the products under treatment as well as with respect to the machinery and of constancy in chemical respects even at high temperatures. They should have also a high specific heat, a high specific weight and a high boiling point, and the capacity of being readily separated from water so that they may be used over and over again. I have used with good results commercial glucose, Turkey red oil, glycerin, trimethylene glycol. There may be other agents having the above described qualities and equally suitable for my purpose.

For the purpose of illustrating the apparatus in which the process of this application may be carried out, I submit herewith a schematic drawing.

The figure shows a top view of the plant.

In the drawings A represents the compressor, and B the belt that drives it.

C C' are the steam cylinders each of which communicates with the compression cylinders D D'.

E represents the pipe communicating with the source of supply, for example, the head of an oil well or of a storage tank or a pipe line.

The drawing will be further described with respect to the fluid to be operated upon in the form of a gas at the point where it enters the tank F with which the pipe E communicates. The tank F is a cleaning

tank, the gases entering said tank through the pipe E at the top of the tank F depositing rust, oils, water, etc., such as are readily separated by gravity. The gases 5 thus comparatively purified pass out from the tank F through the pipe G which communicates with the upper part of the tank F. They pass through the meter M, the function of which is to measure the quantity 10 of gases which are compressed. The gases enter the low pressure cylinder D. The compressed gases are conveyed by means of the connection shown in dotted lines to the high pressure cylinder D', this connection 15 being preferably located below the apparatus shown. In the high pressure cylinder D' the gases are subjected to that degree of pressure which is required to reduce them to the proper condition for treatment in the 20 further processes of the apparatus and also to give them the necessary power to pass through the remaining portions of the apparatus. From the high compression cylinder D' the compressed gases are brought into 25 the top of the separator H in which the glycerin is recovered. The pipe I connects the bottom of the separator H with the top of the glycerin tank J. The pressure in the separator H is sufficient to raise the liquid 30 in the pipe I. From the bottom of the storage tank J the glycerin is carried through the pipes K—L to the spraying nozzles through which it is injected into each of the compression cylinders in a very finely di- 35 vided condition. The pipe L during a portion of its length is shown as externally cooled by the double pipe water cooler N. The by-pass O is used when the storage tank J is cut out of the system for purposes of 40 cleaning, refilling, replacing or repair. From the upper part of the separator H the compressed hydrocarbons pass into the coil condenser P which may be cooled by the expanded gases in the manner which 45 will be described later. The object of the condenser P is to liquefy the major portion of the hydrocarbon gases. The condensates and unliquefied gases pass through the pipe marked with an arrow from the bottom of 50 the condenser P into the top of the collecting tank Q. The dry uncondensed gases are forced through the pipe R into the compound steam cylinders C C', where such pressure as they may be under will be con- 55 verted into work. These gases as they leave the compound cylinders C C' expand into the separator S where such oils or lubricants as they may have gathered will be removed from them. The expansion of these 60 gases at this point following the conversion of their pressure into energy develops a very material reduction in temperature. The cooled gases leave the separator S through the pipe S'. The relief valve T may be 65 used in starting the apparatus so that the

gas engine shall not work against the load. The relief valve T is closed as soon as the pressure is properly developed.

To return to that stage of the process in which the condensed gases are gathered in 70 the collecting tank Q; the liquid leaves the bottom of that tank through pipe 1 through which it is carried into the condenser 2. The condenser 2 is arranged as a surface condenser being supplied with hot water 75 through the pipe 3 which leaves the condenser at 4. The temperature of the water is so regulated that the liquid shall be heated to the desired temperature, say 60° C. The liquid or gasoline which is not vaporized 80 in the condenser 2 is withdrawn through the pipe 5. The gases which are vaporized by this treatment in the condenser 2 leave the condenser through the pipe 6 and pass into the bottom of the condenser 7. The gases 85 condensed in the condenser 7 leave through the pipe 8 at the bottom of the condenser and from the pipe 8 the liquid is directly collected in steel cylinders or tanks in a well known manner and under conditions 90 which exclude the admittance of atmospheric air or pressure. The condenser 7 is arranged like condenser P and consists of a cylindrical vessel through the interior of which passes the coil 23. This coil 23 is connected with pipe 24 through which cold gas is drawn from the coupling 12 into the coil. These cold gases after passing through the said coil 23 pass out of the cylinder 7 through pipe 17 which is connected with the coil 23 at its other end. Where a greater degree of refinement of the pentanes is desired and more than one pentane condenser is employed, the exit pipe 8 represents the last outlet of the pentane system. Uncondensed gases from the pentane condenser pass out through the pipe 22. The cooling temperature required in the condenser 7, which for convenience may be designated as 100 the pentane condenser, as well as that required for the coil condenser P, which may be called the gasoline condenser is supplied by the system itself in the following manner: The uncondensed dry gases still under the pressure imparted to the system leave 105 the collecting tank Q through the pipe 9 which communicates with the pipe R and thus through the compound cylinders C C' and the oil separator S. As above described the gases leave the separator S passing into the pipe 10, being now extremely cold and a part of this gas may be conveyed through the pipe 11 to the gas engine which drives the belt B. The cold gases otherwise flow 110 onward through the pipe 10 to the cross- T 12. The gas is divided and a part of it passes into the top of the pentane condenser 7. The balance of the cooled gas is conveyed by means of the pipe 13 into the bottom of the gasoline condenser P leaving the 115 120 125 130

same at the top through pipe 14, into the cross-T 15 from which they emerge from the system through the pipe 16. In the cross-T 15 these cold gases coming from the 5 gasolene condenser P are joined by the cold gases which leave the top of the pentane condenser 7 through the pipe 17. The valves 18 and 19 are provided so as to permit the withdrawal of the cold gases from the 10 system without causing them to pass through the gasolene condenser or to permit the regulation of the temperature in the gasolene condenser. The cold gases that leave the system at 16 may be again metered and employed for industrial purposes especially 15 where they contain very volatile noncondensable constituents such as methane.

It will be seen from the above description that my process requires the following essential features: A certain set of hydrocarbons must first be procured in the form of or reduced to gaseous condition. The entire set of hydrocarbons together must then be subjected to compression in the presence of a special heat absorbing agent such as hereinabove described. Certain predetermined parts of the whole set of hydrocarbons must then be either together or separately, while in the compressed condition, 20 brought to liquid form by a reduction of temperature. Where the liquefaction of the gasolene constituent takes place simultaneously with that of the pentane constituent, the temperatures and pressures should 25 closely approximate those at which the pentanes are volatilized in order to obtain the full yield of liquid pentane. Before the pressures or temperatures are permitted to become normal or atmospheric, the pentanes 30 (when they are to be isolated to approximate purity) are liberated in gaseous form from the vessel containing the pentane liquid and they are thereafter subjected to a special treatment selected for each member of the 35 pentane group.

In my claims I use the word pentane as typical of the homologues of the pentanes, all of which I intend to include within the scope of the protection desired, and the 40 words gasolene and methane are employed in a similar typical fashion. Where in the claims I refer to a separated gas, I intend to mean a gas which is no longer in admixture with the original gases in the original 45 proportions; for example, pentane becomes a separated gas as soon as a part or all of the gasolene is withdrawn from the compressed gases irrespective whether the pentane is first liquefied together with the gasolene and subsequently volatilized, or whether 50 the gasolene alone is extracted from the compressed gases and the pentane liquefied separately at a separate or subsequent stage of the process.

What I claim is:

1. The process of separating the pentanes from a volatilized mixture of hydrocarbons which comprises subjecting such mixture to pressure in the presence of a finely divided heat absorbing agent, liquefying such of the compressed gases as normally volatilize at temperatures above approximately 25° C., maintaining in the liquid thus produced the condition of its creation, distilling the pentanes from said liquid, liquefying same and storing same under seal. 65

2. The process which consists in securing a mixture of hydrocarbons in the form of gas, containing as one of its constituents the pentanes, confining said gas and in its 80 confined state subjecting it to pressure in the presence of a finely divided heat absorbing agent and to reduction in temperature until such of the hydrocarbons as normally volatilize above 25° C. are reduced to liquid 85 form, maintaining said liquid in the confined state, and separating therefrom, while confined, by suitably adjusting the temperatures and pressures, the specific hydrocarbons which it is desired to isolate. 90

3. The process which consists in securing a mixture of hydrocarbons in the form of gas, containing as one of its constituents the pentanes confining said gas and in its 95 confined state subjecting it to pressure in the presence of a finely divided heat absorbing agent and to reduction in temperature until such of the hydrocarbons as normally volatilize above 25° C. are reduced to liquid form, withdrawing the unliquefied 100 gases, separating, in the form of gas, from the liquid while confined, by suitably adjusting temperatures and pressures, the specific hydrocarbons to be isolated separately from said unliquefied gases, and collecting them 105 in liquid form under seal, and separately storing the residual liquid. 110

4. A method of obtaining from a gaseous mixture comprising hydrocarbons of "low," "medium," and "high" boiling points, that 115 ingredient having the "medium" boiling point, which comprises compressing the gas mixture, in the presence of a heat absorbing medium, then cooling sufficiently to liquefy the portions having the "medium" 120 and the "high" boiling points, separating the liquefied portion from the gaseous portion, conveying said liquefied portion while still under pressure and without allowing alteration of its composition, to a still, and fractionally distilling the same to obtain said portion having the "medium" boiling point separately from that portion having the "high" boiling point, and from that portion having the "low" boiling point. 125

5. A method of obtaining, in isolated condition, the pentanes from a gaseous mixture comprising pentanes and hydrocarbons of

lower boiling points than pentane, and hydrocarbons of higher boiling points than pentane, which comprises compressing said gas mixture, in the presence of a finely divided heat absorbing medium, then cooling the gas mixture sufficiently to liquefy the pentanes, and the ingredients of the gas mixture having higher boiling points than the pentanes, separating the liquid portion from the gaseous portion, conveying said liquefied portion, while still under pressure, and without allowing evaporation of said pentanes, to a still, fractionally distilling the pentanes therefrom, in a concentrated condition, and out of contact with said ingredients having lower boiling points than said pentanes.

6. A method of obtaining a hydrocarbon of the methane series in the isolated condition, from a mixture of said hydrocarbon with other ingredients respectively more readily and less readily volatile; said process comprising the steps of separating in liquid form, the hydrocarbon desired, in admixture with at least some of the ingredients of higher boiling points, subjecting said liquid, in its unaltered condition, to fractional distillation to separate the hydrocarbon from said ingredients having higher boiling point, in relatively concentrated condition, and collecting the same, while avoiding mixing of said hydrocarbon with the uncondensed gases.

7. The method of obtaining in a continuous process three isolated separated ingredients of the methane series, which comprises compressing mixed hydrocarbon gases of said series in the presence of a finely divided heat-absorbing medium, withdrawing the heat absorbing medium from the compressed mixed gases while maintaining the pressure on said gases, condensing out of such

mixed compressed gases predetermined fractions thereof, one of which consists of gasolene and another of hydrocarbons of the pentane class, by the separate action, upon the pentane while in the form of a separated gas and upon the mixed compressed gases while still in the form of gas, of a third ingredient, methane, the said third ingredient being cooled by expansion from the pressure of the initial compression, prior to its condensing action on subsequent volumes of the mixed compressed gases and after the volume of gasolene and pentane initially compressed with it have been reduced to liquid form, separately collecting and withdrawing the thus condensed first two named ingredients in liquid form and the third ingredient in the form of an expanded gas.

8. A method of obtaining pentanes from "wet" natural gas, which comprises highly compressing said gas, in the presence of a finely divided heat absorbing agent, said agent having the properties of being an absorbent for water, being a good conductor of heat, having good lubricating properties, being inert, toward the constituents of said natural gas, and toward the parts of the machinery, having high specific heat, high specific weight, and high boiling point; then cooling said compressed gases sufficiently to liquefy the pentanes and less volatile materials, subjecting said liquid, in its unaltered condition to a temperature sufficient to vaporize the pentanes, and collecting said pentanes in a concentrated condition.

In testimony whereof I have hereunto set my hand in the presence of two subscribing witnesses.

EMIL SCHILL.
